UNITED STATES PATENT OFFICE.

WILLIAM G. ZETSCHÉ, OF CHICAGO, ILLINOIS.

MUFFLE-FURNACE.

1,322,214.

Specification of Letters Patent.

Patented Nov. 18, 1919.

Application filed February 28, 1919. Serial No. 279,803.

To all whom it may concern:

Be it known that I, WILLIAM G. ZETSCHÉ, citizen of the United States, residing at Chicago, in the county of Cook and State of Illinois, have invented certain new and useful Improvements in Muffle-Furnaces; and I do hereby declare the following to be a full, clear, and exact description of the invention, such as will enable others skilled in the art 10 to which it appertains to make and use the same.

This invention has for its object to provide an improved muffle furnace and has for its particular object to provide a furnace of 15 this character having a plurality of muffles mounted therein to be heated for melting or otherwise affecting the contents thereof and in which the temperature of the several muffles may be readily regulated as desired 20 to produce the desired result.

The particular object of the invention is to provide a furnace of the character set forth which will provide batches of molten metal or other products at more or less regular intervals capable of easy control by the 25 operator and which may, therefore, be maintained continuously in operation with resulting economy of time, fuel and labor.

The invention consists in the features of 30 construction and combinations of parts hereinafter fully described and particularly claimed.

In the accompanying drawings illustrating a suitable embodiment of the invention:

35 Figure 1 is a view in side elevation of a muffle furnace constructed in accordance with the invention.

Fig. 2 is a plan section of the same on the line 2—2 of Fig. 1.

40 Fig. 3 is a vertical section of the same on the line 3—3 of Fig. 1.

Fig. 4 is a plan section on the line 4—4 of Fig. 3.

45 My invention relates particularly to that class of muffle furnaces which are adapted to be heated by gas or other fluid fuel. To this end it comprises the housing 1 of fire brick or other suitable material, which is preferably rectangular in vertical and plan 50 sections. The side walls of said furnace or housing are provided at their upper ends with openings 2 into which the fuel supply pipes 3 project, the latter being preferably connected with a source of supply of gas, 55 coal dust or other fluid fuel or hot products

of combustion. Spanning the end walls of the housing are a plurality of muffles 4, 5 and 6 which are partially projected into one of the side walls of the furnace and span the open space between the side wall and end 60 walls thereof and which extend entirely through the other side wall of the same. Each of said muffles is adapted to be closed at its outer end by means of a removable plug 7. The said muffles are disposed at 65 respectively different elevations and are adapted to be successively heated by the passage of the hot gases from the top of the housing to the bottom thereof from which they are exhausted through the opening 8. 70 The side walls are provided at points substantially midway between the upper muffle 4 and the next lower crucible 5 with openings 9 adapted to be closed by plugs 10. Similar openings closed by the plugs 11 are 75 provided in the side walls substantially midway between the muffle 5 and the next lower muffle 6. Obviously, the muffles will be made of suitable heat resisting material adapted to the purpose. 80

The openings 2 in the opposite side walls of the housing are laterally offset from each other so that the flame issuing from each thereof will not oppose the other. In practice, the muffles 4, 5 and 6 are filled with the material to be heated and fuel is then introduced through the supply pipes 3. The hot products of combustion will pass downwardly through the housing and will be exhausted through the opening 8. The heat 90 will thus be absorbed successively by the muffles 4, 5 and 6 and the latter will become heated gradually successively to the necessary high degree.

The particular object of the invention is 95 to provide a plurality of muffles which may be filled with material to be heated successively so as to maintain the furnace in continuous operation. Thus, for example, the muffle 4 will be first filled with the material, then the muffle 5 and thereafter the muffle 6. The muffle 4 will be first heated to the necessary high degree and may be emptied and refilled, and in this interval, the muffle 5 will have attained the requisite 100 high temperature so that after the muffle 4 has been refilled and at such intervals as may be necessary thereafter, the muffle 5 will be 105 ready to be emptied and refilled and so also, in its due order, the muffle 6. Thus, each of 110

the muffles are successively emptied and refilled so as to produce a relatively continuous supply of the products thereof.

In order that the furnace may be properly operated, to substantially continuously produce product or batches of product at regular intervals, the temperature therein may be regulated by moving the plugs 10 and 11 to admit fresh air into the furnace to become admixed with the hot products of combustion and reduce the temperature thereof, thereby regulating the rapidity with which the muffles 5 and 6 in particular attain the desired temperature.

Obviously, the number of muffles disposed in the housing and the number of openings controlled by plugs 10 and 11 may be changed and varied to accommodate the device to the needs of each instalment. Other structural changes may be incorporated for similar reasons without departing from the invention as defined in the appended claims.

I claim as my invention:

1. A muffle furnace comprising a housing having fuel feed openings in one end thereof and an outlet for products of combustion at its other end; a plurality of muffles

mounted at their ends in the walls of said housing and spanning the space between the fuel feed and discharge openings and 30 adapted to be heated successively as the hot products of combustion pass through said housing, said muffles being spaced from each other and each thereof being open at one end and said open end exposed exteriorly of 35 the furnace, plugs for closing said muffles, and valve-controlled openings in the walls of the housing for admitting fresh air thereto for regulating the temperature within the same. 40

2. A muffle furnace comprising a housing having connection at its upper end with a source of supply of fluid fuel under pressure and provided in its lower end with a discharge opening for products of combustion, 45 a plurality of muffles spanning the interior of the housing at different elevations, there being openings in the walls of the housing at elevations alternating with and disposed substantially in staggered relation to the 50 said muffles, and removable plugs controlling said openings.

WILLIAM G. ZETSCHE.
